UNITED STATES PATENT OFFICE.

ARTHUR P. SANBORN AND ROY C. WILSON, OF OSSINING, NEW YORK.

SPEED-CONTROL AND SIGNAL DEVICE.

1,183,677.

Specification of Letters Patent. Patented May 16, 1916.

Application filed March 4, 1915. Serial No. 12,159.

To all whom it may concern:

Be it known that we, ARTHUR P. SANBORN and ROY C. WILSON, citizens of the United States, residing at Ossining, in the county of Westchester and State of New York, have invented certain new and useful Improvements in Speed-Control and Signal Devices; and we do declare the following to be a full, clear, and exact description of the invention, such as will enable others skilled in the art to which it appertains to make and use the same.

Our invention relates to a train controlling mechanism but more particularly to that class of the latter utilized for reducing the speed of the train at predetermined points along the right of way and at the same time displaying a visible signal within the engine cab.

One object of the invention is to provide train controlling mechanism which will automatically reduce the speed of a train at gradings, crossovers, and the like when the speed exceeds a predetermined rate.

A still further object resides in providing a cab signal controlling mechanism operating in conjunction with the speed controlling means.

A further object is to provide novel means for maintaining a closed circuit until the speed of the train has been reduced.

With these and other objects in view, our invention consists of certain novel details of construction, combination and arrangement of parts as will be more particularly set forth and claimed.

In the accompanying drawings: Figure 1 is a diagrammatic view of all the elements comprising our invention and illustrating the manner of electrically connecting the same, certain of said elements being shown in section; Fig. 2 is a diagrammatic view showing intersecting tracks, the disposition of the track magnets with respect thereto, together with means for energizing said magnets; Fig. 3 is an end elevation of one of the track magnets, the latter being partly in section; also of the movable arm supporting the casing which is shown depending from a fragment of a locomotive pilot beam; Fig. 4 is a front elevation of one of the

track magnets; Fig. 5 is a vertical longitudinal section of the signal casing, the annunciator drop inclosed therein being shown in normal or inoperative position; Fig. 6 is a similar view with the drop in operative position; Fig. 7 is a front elevation of the signal containing casing; Fig. 8 is a transverse vertical section taken through the casing inclosing the service air applying means; Fig. 9 is a front elevation of a speedometer illustrating a fragment of its flexible operating shaft; the adjustable contact, and means for adjusting the contact; Fig. 10 is a vertical longitudinal section of the steam valve, its actuating solenoid, and the communications between the two.

Briefly stated, our invention contemplates the use of a pair of electro-magnets disposed in parallel relation on opposite sides of the track at a grading or crossover and energized by suitable electrical connections, the circuit of which may be controlled by a towerman or otherwise, the magnets being adapted to coöperate with a pair of movable arms carried by the train, one of said arms actuating a switch to close one break in a battery circuit, which latter includes suitable means for affecting the service application of the brakes, the other break being closed by means of the movable arm of a standard speedometer coöperating with an adjustable stop carried by the meter so that when the speed of the train exceeds a rate determined by adjusting the stop, the service brakes will be applied and the train speed reduced; whereas, the other arm co-
operates with a switch which latter closes the battery circuit including a signal lamp and annunciator drop whereby the engineer may be apprised as to the proximity of the crossing simultaneously with the application of the service brakes. To this end, we propose to dispose the two magnets 1 and 2 in parallel relation on opposite sides of the tracks A and B and at a suitable distance from the crossover, each of said magnets comprising an apertured base flange 3 having the centrally arranged web 4 circumscribed by the magnetic coil 5. Disposed upon the flange 3 is a casing C provided with a longitudinally extending slot 7 to

permit the web 4 to protrude therefrom and perform its allotted function. The casing is provided with suitable openings which register with those in the base flange 5 to receive fastening bolts 8 by means of which the magnets may be secured in horizontal relation to the standards 9 as clearly shown in Fig. 3.

The electro-magnets 1 and 2 of track sections A and B are connected with battery 1' by conductor 2' extending from one terminal of battery 1' to one terminal of electro-magnet 1, conductor 3' extending from the other terminal of the latter to one terminal 15 of electro-magnet 2, conductor 4' which connects the other terminal of electro-magnet 2 with electro-magnet 1 of the track B, the free terminal of this electro-magnet being connected by conductor 5' with electro-magnet 2 of track B, which latter is connected by means of conductor 6' with conductor 7', the latter extending to a signal tower or other station which is connected by conductor 8' with the negative pole of battery 1'.

25 Depending from opposite sides of the pilot beam are the two supporting posts or standards 10 having angular casings 11 and 11' secured to the free end thereof. Projecting laterally from the casings 11 and 30 11' are the two arms 12 and 12', which latter are pivoted intermediate their ends to the casing as at 13 and 13'. The inner ends of the arms 12 and 12' or in other words, those portions disposed within the casing, 35 are provided with angularly extending projections 14 and 14' whereas the outer portions of the arms 12 and 12' are provided with enlarged portions 15 and 15'.

Suitably mounted in proper insulated 40 relation within the casings 11 and 11', immediately above the projections 14 and 14', are the two resilient contacts 16, 17 and 16', 45 17'. Extending from one side of the casings 11 and 11' are the two brackets 18 and 18', which latter support the electro-magnets 20 and 20', said magnets being adapted to 50 operate with the resilient contacts 17 and 17' respectively.

In order to protect the arms 12 and 12' 50 we provide each of the casings with the angular guard plates 21 and 21'. As it is necessary to return the arms 12 and 12' to their normal position after the same have left the magnetic influence of the two magnets, we 55 provide springs 22 and 22' and connect said springs to the inclosed portions of the arms 12 and 12' and the end wall of casings 11 and 11' as is clearly shown in Fig. 1.

Conveniently mounted within the engine 60 cab, is a standard speedometer 23 operated by the flexible shaft 24, the lower end of which by means of gears 25 and 26, is suitably connected to the axle as will be readily understood without further description.

This speedometer comprises a dial 27 calibrated in a suitable manner as is usual with instruments of this character. A movable pointer 28 is connected to the shaft 29 of the meter and insulated therefrom, said movable pointer 28 being also provided with 70 a conductor terminal 30, the purpose of which will be hereinafter referred to.

Vertically rising from the upper circumference of the speedometer 23, is a plate 28' having therein an arcuate slot 29' to receive 75 an adjustable contact 31, which latter is provided with an adjusting screw 32 and conductor terminal 33, the purpose of which will hereinafter appear. Also situated within the engine cab within easy view of the 80 engineer, is a casing 34 having in the outer face thereof, an annular opening 35 covered by a glass closure 36 of any desired color while immediately below the opening 35, are the two longitudinally extending 85 slots 37.

Within the casing to the rear of the slots 37, is an annuciator drop 38 having the outer face thereof, formed with the longitudinally extending colored bars 39 adapted to register with the slots 37 when said drop is in operative position and in this connection it is to be understood that the colors of the bars will correspond to the 90 color of the glass closure 36.

Operatively arranged with respect to the drop 38, is an electro-magnet 40 which when energized, actuates the drop as will be readily understood without further description. Also within the casing, immediately 100 to the rear of the glass opening 35, is an incandescent light 41 which, in conjunction with the drop, provides the visible signal hereinbefore referred to. To cause the service application of the brakes, we provide a 105 casing 42 which latter is located anywhere within the engine cab; within said casing projects the branch pipe 43 which is tapped off from the train pipe. Connected with said pipe by means of a housing 44 and 110 valve 45 is an air exit pipe 46. Laterally projecting from the valve 45 in casing 42 is an extension 47 having an arm 48 which is normally held in vertical position, which is the closed position of the valve by a spring 115 49 as clearly shown in Figs. 1 and 8. The upper end of the arm 48 is reduced and projects through an opening 50 formed in the projected extremity 51 of solenoid plunger 52, which latter is reciprocatively 120 mounted in the slot 53 formed in the core 54 of solenoid 55 and from which, it will be seen, when the solenoid 52 is energized, plunger 52 will be retracted, the arm 48 actuated, and the valve 45 opened so as to 125 affect the service application of the brakes and gradually stop the train.

To energize the electro-magnets, solenoid,

and lamp hereinabove enumerated, a battery 56 which is located preferably under the engineer's seat within the engine cab, is connected at its positive terminal by a 5 conductor 57 to one terminal of electro-magnet 20, the other terminal thereof being connected to the resilient contact finger 16 by conductor 57' while extending from the co-operating finger 17 is a conductor 58, the 10 free end of which is connected to conductor terminal 33 on the adjustable stop 32. From the conductor terminal 30 on the movable arm 28, a conductor 59 extends to one terminal of the solenoid 55 and extending 15 from the other terminal thereof to the negative terminal of battery 56, is a conductor 60. Also extending from conductor 57 is a branch conductor 61 which is connected to one terminal of electro-magnet 40, the other 20 terminal thereof being connected by conductor 62 to one terminal of electro-magnet 20', the other terminal of the latter being connected through conductor 63 to the resilient finger 16' while leading from the coacting 25 finger 17', is a conductor 64 extending to one terminal of switch 65, the other terminal of said switch being connected by conductor 66 to the negative pole of battery 56. Also leading from conductors 57 30 and 62 are two conductors 67 and 68 extending to and from the lamp 41.

As it has also been found to be advantageous to close off the steam simultaneous with the service application of the brakes, 35 we provide the steam pipe of the engine with a valve 69 consisting of a casing 69' having therein inlet and outlet openings 70 and 71 respectively. In the interior of the casing is a valve seat 72 having therein two 40 openings 73 adapted to be closed by the valves 74, which latter are provided with a stem 75 which projects through an annular opening formed in the plate 76 secured to the top of the casing and extends a slight 45 distance above said plate to engage one arm of the bell crank lever 77 pivotally supported intermediate its ends upon the standard 78. A spring 79 encircles the valve stem 75 intermediate the bell crank 77 and 50 the gasket 80 to normally maintain the valves 74 in elevated position as clearly understood. The free end of the bell crank 77 projects into an opening formed in an extension 81 of a solenoid plunger 81' which 55 is reciprocatively mounted in the slot 82 formed in the core of the solenoid 83 from which it will become apparent that when this solenoid is actuated, the bell crank lever 77 will be operated to seat valves 74 as will 60 be readily understood without further description. The solenoid 83 may be connected by conductors 84 and 85 respectively, conductor 84 being connected at one extremity to conductor 59 and at its other

extremity to one terminal of solenoid 83, the 65 other terminal of the latter being connected by conductor 85 to conductor 60.

From the foregoing description, it will become apparent that actuation of arm 12 by the track magnet 2 will bring the extension 14 into contact with the resilient finger 17, causing the latter to engage the finger 16 and close one break in the circuit of battery 56. Then if it has been determined to reduce the speed of the train to below thirty 75 miles an hour at this particular crossing, and the train is traveling at or exceeding this speed, the rounded or movable arm of the speedometer will be in contact with the adjustable contact 32 which closes the other 80 break in the circuit and allows a current to flow from the positive pole of battery 56 through conductor 57, electro-magnet 20, conductor 57', contacts 16 and 17, conductor 58, adjustable contact 32, movable arm 28, 85 conductor 59, solenoid 55 and conductor 60 to the negative pole of battery 56, also through conductors 84 and 85 to solenoid 83 so that it will be seen that solenoids 55 and 83 will be energized, their respective 90 plungers reciprocated to operate the service brakes and cut off the steam supply as hereinbefore stated, thus materially reducing the speed of the train until the movable arm of the speedometer 23 leaves contact 32 to 95 break the circuit of battery 56. In this connection, it is to be noted that electro-magnet 20 maintains the resilient finger or contact 17 in engagement with the contact 16 after the initial engagement caused by the movable arm 12 being actuated by the track magnet 2 which arrangement maintains this 100 break in the circuit closed as long as movable arm 28 remains in engagement with the adjustable contact 32. Simultaneous 105 with the actuation of arm 12, arm 12' is attracted by electro-magnet 1 and contacts 16' and 17' will be brought into engagement by means of extensions 14 of the movable arm, thus establishing a circuit from the 110 positive pole of battery 56 through conductors 57 and 61, lamp 41, conductor 62, electro-magnet 20', conductor 63, resilient fingers 16' and 17', conductor 64 to one terminal of switch 65 from the other terminal 115 thereof through conductor 66 to the negative pole of battery 56; also through conductor 61 to electromagnet 40 of the annunciator drop, and from the latter through conductor 62 to the negative pole of the 120 battery which lights lamp 41 and energizes electro-magnet 40 so that its drop will be brought into position simultaneous with the lighting of the lamp in order to warn the engineer of the approaching grade or crossover. Thus it will be seen that we have provided an automatic means for controlling 125 the speed of a train at crossovers, gradings,

and the like which will positively reduce the speed of the train if the latter is exceeding a predetermined rate of speed, and warn the engineer that he is approaching such 5 crossover or grading so that accidents at these points, may be avoided.

Although in the above description, we have specified certain elements as best adapted to perform the functions ascribed to them, nevertheless it is to be understood that various minor changes of form, substance, etc., may be resorted to within the scope of the appended claims without departing from or sacrificing any of the principles of this invention.

We claim as our invention:

1. In an automatic train control and signaling device, the combination with an air controlling means, signaling means and energizing circuits therefor, the circuit of said air controlling means having therein two breaks, that of said signaling means having therein one break, a circuit closing member disposed in the circuit of said air controlling means and adapted to close one break thereof, an additional circuit closing member to close the break in the circuit of said signaling means, a pair of movable arms carried by the train and coöperating with the respective circuit closing members, means governed by the speed of the train to close the remaining break in the circuit of said air controlling means, additional means to retain the circuit closing member in the circuit of said air controlling means in closed position during the operation of the means for closing the second break in said air controlling means, and a pair of electromagnets disposed adjacent the track for coöperation with said arms substantially as and for the purpose set forth.
2. In an automatic train control and signaling device, the combination with an air controlling means, signaling means, and energizing circuits for the same, the circuit of the first referred to means having therein two breaks, that of the second referred to means having therein one break, of a pair of resilient contacts included in each of said 50 circuits, the contacts in the circuit of said air controlling means being adapted to close one break therein, the contacts in the circuit of said signaling means being adapted completely to close the latter, a pair of movable arms carried by the train and coöperating with the contacts in the respective circuits, means controlled by the speed of the train to close the remaining break in the circuit of said air controlling means, and a 55 pair of electromagnets disposed adjacent the track for coöperation with said removable arms substantially as and for the purpose set forth.
3. In an automatic train control and sig-

nal device, the combination with an electromagnet disposed contiguous to the track and means for energizing said magnet, of a battery carried by the train, a circuit supplied thereby, the latter having therein two breaks, a casing depending from the pilot beam of the locomotive, an arm horizontally mounted and pivoted intermediate its ends to said casing, said arm having its inner extremity inclosed within said casing and its outer extremity projecting therefrom to co-operate with said track magnet, a pair of resilient fingers included in said battery circuit and disposed in spaced relation within said casing, one of said fingers being disposed contiguous to the inclosed end of said arm, whereby to be actuated by the latter into engagement with the adjacent finger and close one break in said circuit, an electromagnet included in the latter in operative relation with respect to the last mentioned finger, whereby to maintain the latter in permanent engagement, with the adjacent finger air controlling means included in said circuit, a speedometer carried by the train and having a movable indicator included in said circuit, a stop also included in the latter and adjustably mounted upon said speedometer, means to actuate said movable indicator proportionately to the speed of the train whereby when the latter exceeds a predetermined rate, said indicator will be brought into engagement with said contact member to close the remaining break in said circuit and complete the latter through said air controlling means, substantially as and for the purpose set forth.

4. In an automatic train control and signal device, the combination with a pair of electro-magnets disposed in parallel relation adjacent the track, and means to energize said magnets, of a battery carried by the train, an air controlling circuit supplied thereby, a signal circuit also supplied by said battery, the former having therein two breaks, the latter having one break, a movable arm depending from one side of the train, said arm coöperating with one of said track magnets to close one of the breaks in said air controlling circuit and partially complete the same, air controlling means arranged in the last mentioned circuit, a speedometer carried by the train and having a movable arm included in said air controlling circuit, means to actuate said movable indicator proportionately to the speed of the train, a contact member included in said air controlling circuit and adjustably mounted upon said speedometer to coöperate with said movable indicator and close the remaining break in said air controlling circuit to complete the latter through said air controlling means, signals disposed in said signal circuit, another movable arm de-

pending from the opposite side of the train and coöperating with the remaining track magnet, whereby to close the break in said signal circuit and complete the latter through the signals therein, simultaneous with the actuation of the air controlling means, substantially as and for the purpose set forth.

In testimony whereof we have hereunto set our hands in presence of two subscribing witnesses.
